UNITED STATES PATENT OFFICE.

CHARLES E. ROEHL, OF BROOKLYN, NEW YORK.

AUTOMATIC TRAIN-BLOCKING SYSTEM.

No. 851,776.

Specification of Letters Patent.

Patented April 30, 1907.

Application filed December 16, 1903. Serial No. 185,397.

To all whom it may concern:

Be it known that I, CHARLES E. ROEHL, a citizen of the United States, and a resident of Brooklyn, in the county of Kings and State of New York, have invented certain new and useful Improvements in Automatic Train Blocking and Stopping Systems, of which the following is a specification.

The main object of my invention is to provide means for preventing collisions between railway vehicles, and particularly rear-end collisions due to cars or trains following one another too closely, and the invention is applicable to cars or trains operated by steam, electricity or otherwise, whether such cars or trains are run on the surface, on elevated structures or in subways. In carrying my invention into effect I provide as the principal factor in eliminating, or reducing to a minimum, the danger of such collisions, means for automatically stopping the car or train when the point is reached past which it will be dangerous for such car or train to proceed. This automatic controlling means may operate either to shut off the power or to apply the brakes or to do both of these things, it being preferable to apply the brakes and shut off the power at substantially the same moment. This automatic action may be entirely independent of any control by the engineer or motorman, or it may be controllable by him to permit him to run his train or car past a danger point when the conditions are such that it will be safe for him to proceed at reduced speed. This automatic controlling action, both for steam trains and for electrically-operated cars or trains, is governed electrically, and in the case of electric railways the power required for operating the automatic controlling means and other parts of the system, which will be hereinafter more particularly referred to, is obtained directly from the working conductor, which may be either a trolley-wire or the third-rail. The current in the working circuit may be utilized not only for the purpose of operating the automatic controlling means, but also for actuating suitable means at the track or on a vehicle or both, for giving warning to such a vehicle of its proximity to a danger point, and such warning may be given in any suitable manner. Preferably both a track signal and a signal on the vehicle will be governed by such a danger condition, the signal at the track being ordinarily a visual one, such as a semaphore, and that on the vehicle

being preferably a lamp or group of lamps, which may be red lamps to indicate danger.

I regard as one of the most important features of my safety system such a combination of controlling devices as has been just described, all of which devices are controlled from a single source of energy, so that the separate supervision of a separate controlling circuit, which is ordinarily fed with current from a separate source of energy, is rendered unnecessary.

My invention is particularly applicable to electric railways which embody the third-rail system, which is chiefly used in large cities for surface, elevated and subway work, where it is necessary to run cars or trains close together and under conditions which increase the danger of rear-end collisions, as compared with the operation of inter-urban roads.

One of the objects of my invention is to provide improved and simplified means for operating semaphore or other warning signals on railways, and especially on electric railways in which the track rails are used as part of the return or power circuit, without at the same time incurring the loss of conductivity of one or both of the track rails as a current-carrying medium by the necessity heretofore existing of dividing or cutting-up the same into insulated block sections or lengths, such as has been the practice, for example, in the case of steam railroads employing electrically operated block-signal systems.

Another important feature of my invention is the provision in connection with a block system having danger and cautionary signals for each block, of automatic means controlled by a block-signal for stopping a car or train should it enter the blocked section, the preferred organization of the balance of the system being that in which the danger signal of one block controls the operation of the automatic stopping means for a car or train in the rear of the block on which the danger signal is shown, the danger signal of each block also preferably serving to control the cautionary signal of a block in the rear.

Other features of my invention will be hereinafter described and are illustrated in the drawings, in which

Figure 1 is a diagrammatic view of an electric railway and block-signal system embodying my invention. Fig. 2 is an enlarged

diagrammatic view of one type of electric car, with automatic controlling means thereon embodying my invention. Fig. 3 is a similar view of another type of car similarly equipped. Fig. 4 is a diagrammatic view similar to Fig. 1, of a system embodying a modification of my invention. Fig. 5 is an enlarged detail illustrating in cross section and elevation the construction of the track-contacts and conductors and the traveling contact-makers on the vehicle and the manner in which these coat.

Similar characters designate like parts in all the figures of the drawings.

15 The system which I have shown in Fig. 1 for convenience of illustration is a third-rail system having suitable controlling circuits and devices for carrying out my invention, although it should be understood that my invention may be embodied in other systems utilizing electric or any other form of energy as the means for operating the cars or train. In the system shown, I have indicated at 2 the usual track-rails and at 3 and 3' two vehicles or trains following each other in the direction indicated by the arrow. These track-rails are or may be connected substantially as in ordinary railway systems and need not be divided into block sections, and the trains 25 may contain any desired number of cars, six being the maximum in ordinary practice in large cities. Along this track runs the ordinary working conductor, which in this case is a third-rail 4 occupying a position close to but outside the track rails. In the preferred 30 construction this working conductor or third-rail not only serves as the means for supplying the motive current to the motors on the cars or trains but also as the source of 35 current supply for the various devices used to control the movements of the vehicles, and particularly to stop the same automatically on reaching a predetermined danger point. Such a system is usually divided into sections 40 or blocks and protected by means of block signals, and such is the system shown herein, and hence these block-signals are also controlled in the preferred construction by current supplied from the working conductor 45 or third-rail. Thus it will be seen that the third-rail not only supplies current to the power circuit of a vehicle and to the controlling circuit therefor, but that it serves to supply such current both to a traveling circuit 50 on the vehicle and to a fixed circuit at the track. In addition to this it also serves to operate various translating and controlling devices both on the car and at the track, the circuits on the car or train being always 55 two or more in number and the circuits at the track being usually at least two in number for each block section. That is to say, both a motor circuit on the vehicle and a controlling circuit governing the stopping of such 60 vehicle are traveling circuits, and at least one

and preferably two or more circuits at the track for each block are fixed circuits, and all are supplied with current from the third-rail 4. All of these various circuits may be closed by means of suitable traveling contact-makers on the car or train, which contact-makers will close their respective circuits through suitable track-contacts or track-conductors. A contact-shoe, such as 5, which may be the same as, or similar to, that used in ordinary third-rail systems may be employed to supply current from the working conductor or third-rail 4 to the motor or motors on the car or train, and this shoe also preferably constitutes the traveling contact-maker by means of which the circuits to the block-signals are controlled, although of course a separate contact-maker or shoe may be employed.

One of the principal features which distinguishes the construction of my improved system from usual third-rail systems is the provision of track-contacts or conductors governing certain controlling devices employed in the system. In this case in addition to the third-rail I have shown two other conductors extending along the line of way and preferably adjacent to the third-rail. It is only necessary that these conductors be of sufficient length at each danger point or 50 block to assure the making of the circuit therethrough when the contact-maker on the vehicle comes in contact therewith, but in Fig. 1 said conductors extend along substantially the whole length of the line of way and 55 are only interrupted at the points where they are divided to form portions of different block circuits. One of these conductors controls the setting of the block-signals and the other controls the operation of automatic 60 stopping means on the vehicle moving on the tracks 2. The first of these conductors and the various block sections thereof will be designated generally by 6, and the other conductor and its various sections will in a similar 65 manner be indicated by 7. Each section 6 in Fig. 1 extends the full length of a block and so also does each section of the conductor 7. These track-conductors 6 are connected in circuit with means for operating one or 70 more controlling devices at the track, such as danger and cautionary signals or semaphores, designated generally by *d* and *c*. The means shown for operating these signals in one direction is or may be gravity, and in the other direction is preferably solenoids such as 10 and 11, the former of which controls the danger signal or semaphore and is connected by a conductor 12 to the track-contact or conductor 6, and the other of which controls 75 the cautionary signal and is connected by a conductor 13 to the track-contact or conductor 7 and is in turn connected, as by means of a conductor 15 with the conductor 6 of the preceding block. Thus each danger signal is 80

controlled directly from the conductor 6 of its own block and each cautionary signal is controlled through the connection 15 with the conductor 6 of the preceding block. This organization of the controlling track-circuits permits the simultaneous operation of the danger signal of a block on which a car or train is standing or moving and the cautionary signal of a block in the rear of said car or train, thus indicating to an approaching car or train that it may enter the block controlled by the cautionary signal and proceed therein at reduced speed, but may not enter the block at which the danger signal is displayed. These circuits just described are completed whenever a shoe 5 bridges the gap between the third-rail 4 and a track-contact or conductor 6, when current will flow from the third-rail through the shoe 5, conductor 6, conductor 12 and solenoid 10 to ground and operate the danger signal, as shown on the second block of Fig. 1, and at the same time current from the third-rail and the track-contact or conductor 6 will follow another branch through conductor 15, track-contact or conductor 7 of a succeeding block, conductor 13 of such succeeding block, and a solenoid 11 and operate the cautionary signal *c* of such block in the rear. When the vehicle 3 leaves the block on which it is moving, the solenoids being deenergized, the danger signal displayed on the block left by the train, and the cautionary signal displayed on the succeeding block, will be restored to their normal positions.

For the purpose of bringing a car or train to a stop when a danger point is reached, I may make use of any suitable devices on the train, and these may be operated by current taken from the track-contacts or conductors 7. As these conductors 7 are connected respectively with the conductors 6 of the preceding sections it will be evident that in the system shown the means for stopping a car or train will also be controlled by circuits governed by the block-signals. The point at which the automatic controlling action takes place is preferably adjacent to the cautionary signal controlled by the same conductor 7 through which current passes to operate the automatic stopping means on the car or train. Thus the cautionary signal is displayed and the automatic stopping of the train is effected one or more blocks in the rear of a danger signal set by a preceding car or train. The automatic stopping means on the car or train is preferably operated by a controlling circuit also carried on such car or train and including a traveling contact-maker of any suitable type, such as 20, which makes contact with the conductor 7 only. Thus, when the car 3' reaches the point shown in Fig. 1, and its traveling contact-maker 20 comes in contact with a conductor 7 of a circuit the forward gap in which is closed by the

shoe 5 on the train 3, it will be seen that a complete circuit may be closed through the traveling controlling circuit on the train 3'. This traveling controlling circuit is or may be suitably grounded on the train 3', as is the 70 motor circuit, and the circuits of the solenoids for operating the block-signals are also grounded.

In Fig. 2 I have illustrated in detail the manner in which the automatic stopping means on a car is controlled and operated. Here the traveling contact-maker 20 is connected in circuit with a suitable electrically-operated device such as the solenoid 25, governing the movement of a switch, such as 26, 80 for breaking the motor circuit. In this view the controlling circuit for the automatic stopping means from the contact-maker 20 is by way of a conductor 27 to a manual controller or switch 28, a conductor 29, another 85 manual controller or switch 30 and the solenoid 25 to ground. The two switches 28 and 30 are normally closed, and hence when the system is in the condition shown in Fig. 1 a circuit will be closed from the shoe 5 on the 90 car 3 by way of the connections previously traced to the contact-maker 20 on the car 3', from which the current will follow the path just described with reference to Fig. 2 to ground. The consequent energization of the 95 solenoid 25 breaks the circuit of the automatic switch 26 and thus interrupts the motor circuit, which in this case extends from the conductor 5' connecting a pair of shoes 5 at opposite sides of the car, through a conductor 31, a manual controller or switch 32, and conductors 33 and 34, which are separated at the contacts spanned by the switch 26, the remainder of the motor circuit not being shown but being that which is well 100 understood in the art. The breaking of the motor circuit of course shuts off the power and at the same time the brakes of the car or train may be applied in any suitable manner.

In Fig. 2 I have illustrated a well-known type of air-brake apparatus, in which 40 indicates a train-pipe and 41 a brake-pipe having a brake-valve 42, which is also operated by the solenoid 25, both the switch 26 and 115 the brake-valve 42 being connected with the core of the solenoid. Thus, when the solenoid 25 is energized the valve 42 is also operated to release the air pressure or break down the vacuum, as the case may be, and 120 apply the brakes. It should be understood that all of the traveling contact-makers will be so constructed and connected as to be capable of operation at both sides of the car by which they are carried, and one or more 125 such contact-makers may be used on each side of the car. In this case each car or train has at least two shoes 5 on each side of the car for making contact with the third-rail and with the conductor 6, so that there 130

will be at least four such shoes on each train. In a similar manner the traveling contact-makers 20 which coact with the conductor 7 also have at least four points of contact for each train. All of the shoes or contact-makers 5 are suitably connected by conductors 5' and 5'', and the contact-makers 20 may also be connected in a similar manner.

In addition to providing means for stopping a car or train automatically when a danger point is reached I deem it desirable to provide means for visually indicating on such car or train the presence of such danger condition. This I do in the present case by means of lamps, which will be preferably red lamps, connected in circuit with the contact-makers 20. One such circuit, containing a series of lamps, is indicated at 50 and is connected from the conductor 27 to ground, and another is shown at 51 and is connected from conductor 29 to ground. It will be noticed that the lamps in the circuit 50 will be lighted when the danger point is reached, regardless of the positions of the manual switches on the car in the controlling circuit of the solenoid 25, whereas the circuit of the lamps 51 may be broken should the motorman desire to proceed past such a danger point at a reduced speed. This he may accomplish by opening either of the switches 28 and 30, as will be evident.

In Fig. 4 I have illustrated a modification of the invention, in which the track-contacts which coact with the contact-makers 20 do not extend the entire length of each block but are short conductor sections or track-contacts, such as 7'. With these track-contacts it will be seen that the traveling contact-makers 20 are in engagement for only a small portion of the length of a block. In other respects, however, this system is substantially identical with that illustrated in Fig. 1, and the same reference characters for the other parts apply to both.

In Fig. 5 I have illustrated in detail one mode of supporting and constructing the traveling contact-makers and the contact-rails with which they coact. In this view the third-rail is surrounded at its points of support by suitable insulating material between the under side of the tread and the flange of the rail, this insulation being held in place by a tie-bolt, such as 60, in a well-known manner. The separate conductors or track-contacts with which the traveling contact-makers on the vehicle make contact are here shown as angle-rails 6 and 7, the former being secured to one corner of the insulating block by suitable bolts, such as 61, or in any other desired manner, while the latter is mounted in a corresponding manner at the opposite side of the third-rail and at the opposite corner of the insulating support. The upper or contacting surfaces of these auxiliary track-rails or track-contacts are or may

be in the same plane as the contact surface of the third-rail itself. The shoe 5 which coacts with both the third-rail and the angular rail or track-contact 6 is here shown as substantially similar in construction to ordinary third-rail collecting shoes, but is somewhat wider, so as to span both the rail 4 and the rail 6 and bridge the gap between them, the shoe having lugs, such as 65, to which may be pivoted the usual links (not shown) or other devices for connecting it with a car. In a similar manner the contact-maker or shoe 20 may make traveling contact with the upper side of the angular rail or track-contact 7 and has a lug 66 by means of which connection with the vehicle may be made in a manner similar to that just described, these two shoes 5 and 20 being, however, preferably mounted entirely independent of each other.

In Fig. 3 I have illustrated a slightly different type of car from that shown in Fig. 2, the solenoid and the circuit for controlling the same and the circuits of the danger-indicating lamps on the car being identical with corresponding elements shown in Fig. 2, the only differences being in minor features of construction which distinguish the Westinghouse system from the Sprague system.

What I claim is:

1. In a system for controlling the movements of electrically-operated railway vehicles, the combination with the power circuit, of a track-signal circuit governed by the power circuit, a controlling circuit on the vehicle governed by said track-signal circuit, and automatic means governed by said controlling circuit for breaking the power circuit on the vehicle and applying a brake.

2. In a system for controlling the movements of electrically-operated railway vehicles, the combination with the power circuit, of automatic means for stopping the vehicle energized by current derived from the power-circuit, and block-signal circuits for danger and cautionary signals the circuit of each danger signal controlling the circuit of a succeeding cautionary signal and also controlling the automatic stopping means.

3. In a system for controlling the movements of electrically-operated railway vehicles, the combination with the power circuit, of automatic means for stopping the vehicle energized by current derived from the power-circuit, and block-signal circuits for danger and cautionary signals said circuits forming branches of the power circuit and the circuit of the danger signal controlling the circuit to a succeeding cautionary signal.

4. In a system for controlling the movements of electrically-operated railway vehicles, the combination with the power circuit, of automatic means for stopping the vehicle, and block-signal circuits for danger and cautionary signals said circuits forming

- branches of the power circuit and the circuit of the danger signal controlling the circuit of a succeeding cautionary signal and also controlling the automatic stopping means.
- 5 5. In a system for controlling the movements of electrically-operated railway vehicles, the combination with the power circuit, of traveling contact-makers located in different positions crosswise of the vehicle, automatic means for stopping the vehicle, and two sets of track-contacts coöperative respectively with said traveling contact-makers one of the track-contacts controlling a track-signal and the other controlling said automatic stopping means.
- 10 6. In a system for controlling the movements of electrically-operated railway vehicles, the combination with the power circuit, of traveling contact-makers located in different positions crosswise of the vehicle, automatic means for stopping the vehicle, and two sets of track-contacts one set for each block coöperative respectively with said traveling contact-makers one of the track-contacts controlling the track-signal and a dissimilar track-contact of a block in the rear being connected with said first track-contact and controlling said automatic stopping means.
- 15 7. In a system for controlling the movements of electrically-operated railway vehicles, the combination with the power circuit, of traveling contact-makers located in different positions crosswise of the vehicle, automatic means for stopping the vehicle, and two sets of track-contacts one set for each block coöperative respectively with said traveling contact-makers, one of the track-contacts controlling a danger signal on its own block and a cautionary signal on a block in the rear and a dissimilar track-contact of said block in the rear being connected with said first track-contact and controlling said automatic stopping means.
- 20 8. In a system for controlling the movements of electrically-operated railway vehicles, the combination with a third-rail, of a signal-conductor adjacent to said third-rail, automatic stopping means controlled by said signal-conductor, and a traveling contact-maker on the vehicle spanning said third-rail and signal-conductor for supplying current to the motor-circuit and to the signal-conductor.
- 25 9. In a system for controlling the movements of electrically-operated railway vehicles, the combination with a third-rail forming a continuous working conductor, of a track-contact adjacent to said third-rail and forming a part of a block-circuit, a block-signal controlled by said block-circuit, and a traveling contact-maker on the vehicle and spanning said third-rail and track-contact for supplying current to the motor circuit and to the block circuit.
- 10 10. In a system for controlling the movements of electrically-operated railway vehicles, the combination with a third-rail forming a continuous working conductor, of danger and cautionary signals, a track-contact adjacent to the third-rail and connected in block-circuits controlling danger and cautionary signals of different blocks, and a traveling contact-maker on the vehicle and spanning said third-rail and track-contact for supplying current to the motor circuit and to the block-circuits.
- 15 11. In a system for controlling the movements of electrically-operated railway vehicles, the combination with a third-rail, of a pair of track-contacts adjacent to and located in different positions with respect to said third-rail and forming parts of block-circuits, a block-signal controlled by one of said block-circuits, automatic stopping means controlled by the other block-circuit, and a pair of traveling contact-makers on the vehicle one spanning said third-rail and the first track-contact and the other coacting with said second track-contact.
- 20 12. In a system for controlling the movements of electrically-operated railway vehicles, the combination with a third-rail, of a pair of track-contacts adjacent to and located in different positions with respect to said third-rail and forming parts of block-circuits in which dissimilar track-contacts of different block-circuits are connected, a block-signal controlled by one of said block-circuits, automatic stopping means controlled by the other block-circuit, and a pair of traveling contact-makers on the vehicle one spanning said third-rail and the first track-contact and the other coacting with said second track-contact.
- 25 13. In a system for controlling the movements of electrically-operated railway vehicles, the combination with a third-rail, of danger and cautionary signals, a track-contact adjacent to the third-rail and connected in block-circuits controlling danger and cautionary signals of different blocks, a second track-contact adjacent to said third-rail but occupying a different position and connected in circuit with the cautionary block-circuit of its own block, automatic stopping means controlled by said second track-contact, and a pair of traveling contact-makers on the vehicle one spanning said third-rail and the first track-contact and the other connected with said second track-contact.
- 30 14. In a system for controlling the movements of railway vehicles, the combination with a block-signal circuit, of a controlling circuit governed by said block-signal circuit and controlling a block in the rear of that controlled by said block-signal circuit, and automatic stopping means carried by the vehicle and governed by said controlling circuit.

15. In a system for controlling the movements of railway vehicles, the combination with block-signal circuits having danger and cautionary signals, in which the circuit of each danger signal controls the circuit of a succeeding cautionary signal, of automatic stopping means located upon the vehicle and governed by the circuit of the cautionary signal.
16. In a system for controlling the movements of electrically-operated railway vehicles, the combination with a power circuit, of a controlling circuit on the vehicle said circuit containing a manual controlling switch and being governed by the power circuit, and an automatic controlling device also on the vehicle and governed by the controlling circuit.
17. In a system for controlling the movements of electrically-operated railway vehicles, the combination with the power circuit, of a controlling circuit on the vehicle said
- 15 circuit containing a manual controlling switch and an indicator and being governed by the power circuit, and an automatic controlling device also on the vehicle and governed by the controlling circuit.
18. In a system for controlling the movements of electrically-operated railway vehicles, the combination with the power circuit, of a controlling and lighting circuit on the vehicle said circuit containing a manual controlling switch and one or more lamps and receiving current from the power circuit, and an automatic controlling device also on the vehicle and governed by the controlling circuit.

Signed at New York in the county of New York and State of New York this 15th day of December A. D. 1903.
